**BAG TOP CLOSURES FOR CONSUMER
SIZE BAGS**

Harold K. Fox, Minneapolis, Minn., assignor to Bemis
Bro. Bag Company, Minneapolis, Minn., a corporation
of Missouri

Filed Nov. 6, 1963, Ser. No. 321,922
7 Claims. (Cl. 229—62)

This invention is directed to providing a bag top closure of a construction that will prevent a finely divided product from sifting through the folds adjacent the end flaps of the closure. More particularly this invention is directed to providing a sharp and flat fold in overlapping portions of a bag top closure to prevent product sifting therethrough.

Flour, sugar and similar other products are frequently sold in consumer size bags in five and ten pound quantities having a Deltaseal bag top closure, Deltaseal being a registered trademark of the assignee of this application, and of a construction generally disclosed in U.S. Patents 1,868,686 and 1,937,506. Such closures, which are generally made with automatic equipment, consist of two sets of folds with adhesive applied between the folds. Problems have been encountered with the second set of folds due to the two thicknesses of paper of the sideflaps that fold over together. That is, the inner sheet will buckle or crumple up (if both sheets are the same length) because of the effective smaller radius of the inner sheet. Therefore, a sharp flat fold cannot be obtained. However, a fold must be sharp and flat to preclude a finely divided product from sifting through at the fold. That is, usually in using the processes of the prior art, a small channel remains adjacent the second set of folds and as a result sifting occurs. This invention is directed to overcoming the aforementioned problem.

One of the objects of this invention is to provide a new and novel bag top closure made up of two sets of folds wherein the folds will be sharp and flat to prevent product sifting therethrough. A further object of this invention is to provide in a bag top closure of the general type illustrated in FIGURES 22 and 6 respectively of U.S. Patents 1,868,686 and 1,937,506 a new and novel seal in the area of the fold lines to prevent sifting of product therethrough. Still another object of this invention is to provide a plurality of slits in the bag top at the time of bag manufacture such that the slits subsequently will be adjacent the fold lines of the side wall flaps and permit adhesive bleeding through the slits to form a positive seal in this area.

Other and further objects of this invention are those inherent in the invention herein illustrated, described and claimed, and will be apparent as the description proceeds.

To the accomplishment of the foregoing and related ends, the invention then comprises the features herein-after fully described and particularly pointed out in claims, the description setting forth in detail certain illustrative embodiments of the invention, these being indicative, however, of but a few of the various ways in which the principles of the invention may be employed.

The invention is illustrated with reference to the drawings in which corresponding numbers refer to the same parts and in which:

FIGURE 1 is a vertical view of an empty bag in a flat folded condition that has been slit in accordance with this invention;

FIGURE 2 is an enlarged fragmentary perspective view of the top portion of the bag of FIGURE 1 after it has been filled and adhesive applied to the inner surface of one end panel and adjacent portions of the side panels.

FIGURE 3 is a view similar to FIGURE 2 other than the one end panel has been folded down;

FIGURE 4 is a fragmentary perspective view of filled bag after the second step of the folding operation has been completed;

FIGURE 5 is a plan view of the filled bag after adhesive has been applied to the flaps and the flaps have been moved upwardly intermediate the position of FIGURE 2 and a completely folded and sealed position;

FIGURE 6 is an enlarged fragmentary vertical cross sectional view generally taken along the line and in the direction of the arrows 6-6 of FIGURE 5, the FIGURE 5 position of the flaps being illustrated in solid lines and the dotted line position illustrating the flaps in the FIGURE 4 position;

FIGURE 7 is a further enlarged fragmentary plan view of a partially folded flap, said view being generally taken along the line and in the direction of the arrows 7-7 of FIGURE 6, other than no adhesive is shown, to illustrate the spreading of the tabs at the fold line of the flap;

FIGURE 8 is an enlarged vertical cross sectional view illustrating the effective smaller radius of the inner sheet of a flap relative to the outer sheet, said view being generally taken along the line and in the direction of the arrows 8-8 of FIGURE 4 other than the flap has nearly been folded to a flap sealed position;

FIGURE 9 is an enlarged view of one corner portion of FIGURE 2; and

FIGURE 10 is a plan view of a filled bag with the top thereof folded and sealed in accordance with this invention.

The bag 10 shown in FIGURE 1 is of the type commonly known as a "flat bag" other than each of the body walls adjacent the top edges (adjacent the bag mouth) has been provided with a plurality of slits or cuts at the time of the bag manufacture. The bag 10 has a thumb notch 11 and when in the "flat" condition of FIGURE 1 has its body walls folded flatwise relative to one another for convenience in storage and packaging, the two body walls being joined at contiguous edges in a manner to leave on open bag mouth.

The aforementioned cuts are made at the top of the bag, both walls, more closely adjacent to one joined edge of the flat bag than the other as illustrated in FIGURE 1 and extend generally parallel to the edges of the flat folded bag. Thus if the bag is provided with six cuts as illustrated in FIGURE 1, the five small tabs 12 are provided. These tabs are formed in the bag body walls such that when the bag has been opened, filled and shaped to be of a generally rectangular configuration in horizontal plane (see FIGURE 2), one group of tabs will be located in one upper corner portion of the adjacent portions of each of one end wall 15 and side wall 14 and the other group of tabs will be located in the upper adjacent corner portion of each of the same end wall 15 and the opposite side wall. That is, the tabs are formed such that each group will include tabs on either side of the respective fold line F-F for the second set of folding operations as will be set forth hereinafter (see FIGURE 4).

After the bag has been provided with the tabs at the above described locations, it is filled with product (with or without intervening storage and/or shipment) and then at least the upper portion of the filled bag is shaped to be of generally rectangular configuration as illustrated in FIGURE 2 wherein one group of tabs is located at each corner portion of the same end wall. Preferably at this time, an adhesive, for example, a strip of glue or paste 13 is applied to the inner surface of the top portion 15b of the end wall having slits therein and continuing around on portions of the side walls such as illustrated in FIGURE 2. Although less desirable, glue could be applied to the end wall opposite the one having the

slits formed therein such as described in U.S. Patent 1,868,686. Now the top portion (panel) 15a is folded inwardly to be generally horizontal and overlay the material in the bag by a dimension h (see FIGURE 4) and the top portion (panel) 15b of the slotted end wall is folded inwardly to have the portion thereof with adhesive thereon completely overlay a portion of panel 15a.

With reference to the above paragraph, the adhesive 13 is applied to the bag to extend horizontally along the side wall having the thumb cut 11 from adjacent the thumb cut to the end wall 15 having the tabs, along said end wall and thence along the opposite side wall to a location corresponding to the thumb cut in the first mentioned side wall. The strip of adhesive is preferably located at a dimension k vertically above the lower extremities of the slits and is of a vertical dimension L , the length of the slits being a dimension m (see FIGURE 9). During the folding of the bag from the FIGURE 2 condition to that of FIGURE 4 and somewhat during the subsequent folding of the flaps 17 and 18, the glue or paste spreads to cover an area that corresponds to a position in FIGURE 9 at the bottom of the slits or slight below and likewise spreads in the opposite direction. The folding of the bag top to the FIGURE 4 condition and appropriate application of pressure causes the adhesive 13 to adhere to the portion of panel 15a and the portions of parts 14c of the flaps that it overlays.

As a result of the aforementioned two folding steps, the top portions of the side walls are folded to form laterally extending flaps 17 and 18, one flap extending outwardly of each side wall as illustrated in FIGURE 4. Each flap of FIGURE 4, as illustrated in FIGURE 6, includes a triangular part 14a having a base integrally joined to the adjacent edge of the generally vertical side wall 14, a quadrangular part 14b having edges integrally joined to portion 15b and an edge of triangular part 14a, a third part 14c which may be of a triangular or trapezium configuration depending on the dimension h of portion 15a and a fourth part 14d. Regardless of the resulting geometric shape of part 14c it will have one edge integrally joined with portion 15a and a second edge integrally joined with triangular part 14a. Part 14d has one edge integrally joined to a third edge of 14b and another edge likewise joined to a third edge of 14c and is located between overlapping portions of parts 14c and 14b and for the most part adjacent the apex portion of the flap. Thus for the width of the overlapping portions of parts 14b and 14c and in a lateral direction from the adjacent apex A of the respective flap and the adjacent vertical side wall there are three thicknesses of material (14a, 14b, 14c), and adjacent the apex portion a fourth thickness 14d; while for the remaining portion of the flap, there are two thicknesses 14a, 14c and 14b, 14c respectively.

After the upper portion of the bag top has been folded to the FIGURE 4 condition, then adhesive 21 is applied to the then upper surface of each of the flaps to cover substantially the entire surface area thereof. Now flap 18 is folded upwardly about the fold line F—F from the dotted line position of FIGURE 6, through the solid line position thereof and then to the FIGURE 10 position with appropriate application of pressure so that adhesive 21 adheres to the adjacent surface of panels 15a, 15b. Likewise flap 17 is folded to complete the sealed bag top closure illustrated in FIGURE 10.

For each flap for the entire length of each fold line there are at least two thicknesses of material folded about said fold line and in the area of overlap of parts 14b, 14c three thicknesses. As may be seen in part from FIGURE 8, which shows the flaps 17 in a nearly completely folded condition, to obtain a sharp flap fold about fold line F—F the overlapping portions of 14a, 14b have to fold about a single fold line and each should have a single radius of curvature since the perpendicular distance

from the fold line to apex A is the same when they are in the FIGURE 4 position. However due to the thickness of material, the overlapping portion of part 14b will effectively have a shorter radius of curvature than 14c as they are folded through the FIGURE 8 position. As a result, without the tabs of this invention, either 14b and/or usually panel 15b of prior art bag disclosures crumples or buckles to provide this effective shorter radius of curvative and thereby resulting in a small channel through the adhesive seals where sifting can occur. Such a channel can result in automatic folding operations since the adhesive between overlapping portions of panels 15a, 15b has not had a chance to set prior to the initiation of the folding of the flaps.

In using the bag structure of this invention as the bag top is folded from the FIGURE 4 position to the FIGURE 5 position, the cuts eliminate the rigidity of the bag in the area of the fold lines F—F so that the folding can be done with little or no resistance and the folds will follow the line of least resistance in the area of the cuts. That is, during initiating the fold of a flap about the fold line F—F, the folding action tends to spread the adjacent tabs at the fold line as is illustrated in FIGURE 7 since the second thickness 14c is adjacent the first thickness 14b and thereby exerts pressure laterally on the tabs as the fold is being made. This in effect provides only a single thickness of paper to be folded and as a result a sharp fold is obtained.

As the flaps 17 and 18 are folded from the FIGURE 3 position to the FIGURE 6 position, the glue which has been previously applied to adhere the portion of the top enclosure 15b that overlaps portion 15a to panel 15a will bleed through the cuts of tabs 12 to make a better seal in this area. Accordingly a portion of 14c is adhered to the adjacent portion of the folded side wall portion 15b.

From the above it is believed apparent that in folding the bag top closure of the aforementioned U.S. patents, frequently the glue intermediate the adjacent end wall portions 15a and 15b as designated in the drawings of this application does not set sufficiently rapidly to preclude the portion of 15b that overlies portion 15a from pulling apart to form a channel adjacent each of the fold lines. This is in contrast to this invention wherein by providing the tabs, the tendency to form such channels is eliminated. Additionally due to the bleeding of the glue through the tabs, each flap part 14c in the area of the tabs is adhered to the underlying portion of panel 15a, and accordingly provides a positive seal in this area.

As an example of the invention but not a limitation thereon the following dimensions are given. For consumer-size bags of five pound and ten pound quantities, six cuts have been provided on each side wall, such that each tab thereby formed is $\frac{7}{16}$ " long and $\frac{3}{16}$ " wide. However, it is to be understood that these cuts can be varied in size and number to fit any specific application in which this invention is to be used. The dimension L is approximately $\frac{1}{8}$ ", the dimension k $\frac{1}{8}$ " and the dimension m $\frac{7}{8}$ ". Likewise the aforementioned dimensions are given as an example of the invention but not as a limitation therein since they can be varied to fit any specific application in which this invention is to be used.

As many widely apparent different embodiments of this invention may be made without departing from the spirit and scope thereof, it is to be understood that I do not limit myself to the specific embodiments herein.

What I claim is:

1. A bag in a flat folded condition having adjacent body walls joined at contiguous edges and having an open bag mouth, each of said walls having a plurality of slits extending generally parallel to provide a plurality of tabs at the portion of the respective wall adjacent the bag mouth, said tabs being located more closely adjacent one of said edges than the other and substantial spaced from each of said edges.

2. A bag body in open upright condition and shaped to have at least its upper portion of a generally rectangular configuration to provide side walls and end walls, said side walls and end walls being joined at contiguous edges, one end wall having two groups of a plurality of vertical slits to form tabs at its upper portion, one group being located adjacent each side wall.

3. A bag closure for an end portion of an upright bag body in open condition that in at least the upper portion thereof is of a generally rectangular configuration to provide side walls and end walls that are joined at contiguous edges to form four corner portions comprising a first panel joined to one end wall, a second panel joined to the opposite end wall and in part overlapping the first panel, a first flap having a first portion joined to one side wall, a second portion joined to one edge of the first panel and a third portion joined to one edge of the second panel and at least in part overlaying said panels, a second flap having a first portion joined to the other side wall, a second portion joined to an opposite edge of the first panel, and a third portion joined to an opposite edge of the second panel and at least in part overlaying said panels, said second portions and second panels each having a group of slits forming tabs, the tabs in each portion and the respective second panel being adjacent one another, and adhesive adhering the panel overlapping portions to one another, both the second and third portions of each flap to one another and to the second panel in the area of the respective group of tabs, and non-tabbed areas of the second portions to areas of the second panel against which they abut.

4. The structure of claim 3 further characterized in that each of said panels is generally of a rectangular configuration, that each of said flaps is generally of a triangular configuration and that each group of tabs is located adjacent the respective side wall.

5. A bag closure for an end portion of a bag in a filled condition that is in at least the upper portion of a generally rectangular configuration to provide side walls and end walls comprising a first end wall panel, a second end wall panel that at least partially overlaps the first end wall panel, said end wall panels being adhered to one another along their overlapping portions, a first general triangular flap overlaying a portion of said panels and adhered to at least one of said panels, said first flap including a first triangular part having one edge integrally joined to one side wall and two quadrangular parts each of which is integrally joined to a different panel and a second general triangular flap overlaying a portion of said panels and adhered to at least one of said panels, said second triangular flap including a triangular portion having an edge integrally joined to the opposite side wall, the adjacent

panel and quadrangular part being slotted to form tabs adjacent the juncture of the first triangular portion to the side wall and both of said quadrangular parts and both of said panels being adhered to one another at said tabs.

- 5   6. A bag body in an upright condition, having an open
end, and shaped to have at least the portion adjacent said
open end of a generally rectangular configuration to pro-
vide side walls and end walls, said side walls and end
walls being joined to form four corner portions adjacent
10 the open end, two adjacent corner portions each having a
plurality of slits that intersect the open peripheral edge
of the bag body to form generally vertical tabs.
7. A bag closure for an end portion of an upright bag
body in an open condition that in at least the upper por-
15 tion thereof is of a generally rectangular configuration to
provide side walls and end walls that are joined at con-
tiguous edges to form four corner portions comprising a
first panel joined to one end wall; a second panel joined
20 to the opposite end wall and in part underlapping the first
panel; a first flap having a first portion joined to one edge
of the first side wall, a second portion joined to one edge
of the first panel and to one edge of the first flap first
portion and having a free edge, and a third portion joined
25 to one edge of the second panel; a second flap having a
first portion joined to the other side wall, a second portion
joined to an opposite edge of the first panel and to an
edge of the second flap first portion and having a free
edge, and a third portion joined to an opposite edge of
30 the second panel; each of said second portions having
surface portions intermediate the respective first portion
and at least one of the panels; said second portions in the
area of said surface portions each having a group of slits
extending generally perpendicular to the respective free
35 edge and located closely adjacent a wall; and adhesive
adhering panel underlapping portions to one another,
the surface portions of said panels that abut against said
flaps to said flaps including the area of the second por-
tion adjacent the tabs to both the first panel and to the
respective first portion.
